UNITED STATES PATENT OFFICE.

EDWARD WESTON, OF NEWARK, NEW JERSEY, ASSIGNOR TO THE UNITED STATES ELECTRIC LIGHTING COMPANY, OF NEW YORK, N. Y.

APPARATUS FOR TREATING CARBON CONDUCTORS.

SPECIFICATION forming part of Letters Patent No. 289,827, dated November 27, 1883.

Application filed July 31, 1883. (No model.)

To all whom it may concern:

Be it known that I, EDWARD WESTON, a subject of the Queen of Great Britain, and a resident of Newark, in the county of Essex and State of New Jersey, have invented certain new and useful Improvements in Apparatus for Treating Carbon Conductors, of which the following is a specification, reference being had to the drawings accompanying and forming a part of the same.

The process of treating carbons and the apparatus for use in the same, to which this invention relates, are as follows:

A number of carbons are prepared from any suitable carbonizable material, all being as nearly as possible of the same size and resistance. One or more of these are then mounted on temporary clamps and covered by a globe or receiver communicating with an air-pump. By means of this latter the air is withdrawn from the receiver, and its place then filled by a hydrocarbon vapor, which is admitted through a pipe from a gasoline-tank or other gas-supply. This vapor is then partly withdrawn and the current passed through the carbons, a current of sufficient strength being employed to bring them to a red heat. By this means carbon is dissociated from the surrounding vapor and deposited on the conductor, gradually lowering its electrical resistance. When the standard resistance is reached, the current is interrupted, air is admitted under the receiver, and the carbons removed. The necessary degree of exhaustion of air and attenuation of the hydrocarbon is readily attained by the employment of any good form of mechanical air-pump, and one or two of such pumps, driven or operated by steam or water power, are generally used. In practice it has been found that these pumps require constant attention and repair, so much so that the expense of carrying out the process by their use is very greatly increased. This I have found to be due to the rapid destruction and cutting of the valves and moving portions in contact in the pump by the fine and hard particles of carbon precipitated from the hydrocarbon vapor by the action of the current and carried down through the connecting-pipes from the receiver into the

pump. I avoid this difficulty and preserve 50 the pump from the destructive effects of carbon-dust by interposing one or more filters between the treating apparatus and the pump, and in this combination my invention is mainly comprised.

In describing more in detail the nature and purpose of the invention, reference will be made to the accompanying drawings, in which—

Figure 1 is a diagram illustrating the principal parts of a complete treating apparatus. 60 Fig. 2 is a central section of the filter devised by me. Fig. 3 is a detail of the same.

Similar letters of reference indicate corresponding parts in the several figures.

A is a metal plate, upon which the receiver 65 or exhaust-chamber B is fitted in any of the usual ways.

C is a tube leading up through the plate A, under the receiver B, and connecting with a mechanical air-pump, D. Connecting with 70 the pipe C is a pipe, E, from a cylinder, F, for containing a volatile hydrocarbon or any other form of reservoir, from which a carbon-bearing vapor may be introduced into the receiver. Stop-cocks e and e' are inserted in the pipes C 75 and E at the points indicated.

Surrounding the orifice of pipe C on the plate A are a given number of clamping devices, G, for retaining the carbons to be treated, and with the clamps are connected the conductors H H, by which the current is introduced. Over the orifice of pipe C is a brass cup, K, with perforated top, and containing a small quantity of wool, cotton, or any material, to serve as a filter and intercept particles 85 of carbon or other substances and prevent the same from passing down into the pump. In the tube or pipe C, at any convenient point between the pump D and the treating apparatus, is inserted a cylinder of metal, L, divided off into three compartments, a' b' c', by plates M. These plates are perforated, or composed of wire gauze, except at their centers, which are without perforations, and designed to break the column or jet of air which rushes 90 in when the receiver B is removed.

The plates M are secured in any manner in the cylinder L, and between them is placed a

quantity of wool, cotton waste, or any other material capable of intercepting the carbon particles and preventing them reaching the pump.

5 While the form of filter described has certain advantages, I do not restrict myself to its use alone, as any other convenient form may be substituted for it.

In using the apparatus one or more carbons are placed in the clamps G and covered by the receiver or bell-jar B. Communication with the reservoir F is then shut off and communication with the pump opened by means of the cocks e and c, respectively. The air is then withdrawn from the receiver until a high vacuum is produced, when the pump is shut off and vapor admitted from the reservoir F. This is then partially pumped out, and the current passed through the carbons until they have received the necessary treatment. Air is then admitted under the jar B by a two-way cock, f, and the carbons removed. When the next treating is begun and communication between the receiver B and pump D established, a rush of air to the pump occurs, that carries along with it the carbon-dust that has found its way into the pipes C and E until it reaches the filter L.

Although I have shown two filters, K and L, I may, without injury to the apparatus, dispense with one, in which case I prefer to retain the filter L.

The specific construction of the filters is not herein claimed, the same being reserved for subject of another application.

Without reference, then, to the specific character of the apparatus, the pump, or the filter, and reserving as subject of other applications features of novelty herein shown or described but not claimed, what I now claim is—

1. In a carbon-treating apparatus, the combination, with the pipes or tubes, of one or more filters located between the treating chamber or receiver and the air-pump, substantially as and for the purpose set forth. 40

2. In a carbon-treating apparatus, the combination, with a treating-receiver, a mechanical air-pump, and tube or pipe connecting the same, of a filter placed in said tube for intercepting particles of carbon or other matter, as 50 and for the purpose specified.

3. In a carbon-treating apparatus, the combination, with a treating-receiver, B, gas-tube E, air-tube C, and mechanical pump D, of a filter placed in the tube C, for intercepting particles of carbon or other matter, as and for the purpose set forth. 55

In testimony whereof I have hereunto set my hand this 30th day of July, 1883.

EDWARD WESTON.
